UNITED STATES PATENT OFFICE.

FRANK W. BARBER, OF CHICAGO, ILLINOIS.

CABLE TIGHTENER.

Application filed August 28, 1922. Serial No. 584,718.

To all whom it may concern:

Be it known that I, FRANK W. BARBER, a citizen of the United States, residing at Chicago, in the county of Cook and State of Illinois, have invented certain new and useful Improvements in Cable Tighteners, of which the following is a specification, reference being had to the accompanying drawings, and to the reference characters 10 marked thereon, which form a part of this specification.

This invention relates to devices for tightening cables or lines, commonly called a tourniquet, and it consists in the novel device and combination of parts herein illustrated, described and claimed.

In the drawing:

Fig. 1 is a perspective view of the tourniquet in use, as applied to a clothes line.

20 Fig. 2 is a side view of the device, enlarged, with a portion at each end in section.

Fig. 3 is a top plan view of the device, showing its attachment to a line or cable.

25 Fig. 4 is an elevation showing one end.

In the drawing, I have shown one post A, such as an ordinary clothes post, provided with a hook 1. The clothes line B will be secured at its ends to the hooks 1 30 upon the posts A, and drawn as taut as may be possible, but to take up slack or sag in the line when clothes are hung upon it, my improved tourniquet will be found desirable.

35 This device consists of a rod or bar C, usually of wood, and preferably about one inch in diameter, and fifteen to eighteen inches in length, or thereabouts. Surrounding the rod C and near one end is a metal

40 tubular member or sleeve D. Through the bar C near the same end is a slot or elongated aperture 2, through which the bent portions of a cleat E are passed. A tubular sleeve D of a diameter to fit over the

45 bar C is provided with two diametrically opposite apertures 3, 4, through which, when the sleeve is positioned over the bar aperture 2, the parts of the wire cleat may be passed.

50 The cleat E is of metal, preferably of wire bent in U shape, the loop portion of the wire being secured, by a pin 5, to the sleeve D; its two U-shaped members being held apart by a spreader member 6. This spreader may be part of the bar C, by bor-

ing two parallel apertures 2, or it may be a separate piece, as shown. The ends 7, 7, of the cleat E, after being passed through the apertures 3 and 4 of the sleeve, and aperture 2 of the bar C, are spread or flared 60 outwardly or away from each other as shown. In the other end of the bar C, I use a securing member F which consists of a screw threaded arm 8 and a loop or hook end 9. The other end of the bar C, I prefer to chamfer off or cut away somewhat, as shown at 10.

The operation of the tourniquet will be readily understood without special instructions, since the user will simply place the cleat E sidewise against the line B, and by turning the rod about the cleat E, will take up the slack in one or any number of coils 12 required. When the line B has been thus tightened, the rod C is hung on the line by 70 engagement of the hook F therewith, thus locking the device in position.

In the application of the tourniquet to a line, it will be found convenient to grasp the line B with one (say the left) hand at 80 a point near where the cleat is to engage the line, and to grasp the bar C with the other hand near the end having the hook F. By holding this handle end somewhat away from the line B, so that the bar C will be at an angle to and not parallel with the line B, the turning or crank movement of the bar C will be facilitated and the hand of the operator on the bar C will not be scraped 85 by contact with the line B. For this reason, and to insure ease of movement, I chamfer off the end at 10, the line readily slipping over this surface during the turning movement.

90 The device is simple, cheap to manufacture, easy to assemble, has no complicated parts to get out of order and is found to be most efficient in use.

I claim as my invention:

1. A cable tightener comprising a handle 100 bar having an opening therethrough, a wire bent between its ends and located in said opening, the ends of the wire projecting beyond one end of said opening and being spread apart to form a cleat and means on the bar at a point remote from the cleat adapted to engage a cable after the slack therein has been taken up by the cleat.

2. A cable tightener comprising a handle 110 bar having an opening therethrough, a wire

- bent between its ends and located in said opening, the ends of the wire projecting beyond one end of said opening and being spread apart to form a cleat, means on the 5 bar at a point remote from the cleat adapted to engage a cable after the slack therein has been taken up by the cleat, and means for locking the wire to the bar.
3. A cable tightener comprising a handle 10 bar having an opening therethrough, a wire bent between its ends and located in said opening, the ends of the wire projecting and being spread apart to form a cleat and means on the bar at a point remote from the 15 cleat adapted to engage a cable after the slack therein has been taken up by the cleat, and a spreader member in the rod between the bent portions of the wire.
4. A cable tightener comprising a handle 20 bar having an opening therethrough, a wire bent between its ends and located in said opening, the ends of the wire projecting and being spread apart to form a cleat and means on the bar at a point remote from the 25 cleat adapted to engage a cable after

the slack therein has been taken up by the cleat, and a spreader member in the bar between the bent portions of the wire, and a sleeve surrounding the bar and wire.

5. A device for tightening cables comprising 30 a cylindrical bar, an opening therethrough near one end, a U-shaped wire in the opening with its ends projecting therefrom and spread apart to form a cleat, a spreader member in the bar opening between the two parts of the U-shaped wire, a metal sleeve surrounding the bar, openings in the sleeve to cooperate with the wire, a pin for fastening the wire to the sleeve, and a cable engaging hook secured to the 35 other end of the bar.

In testimony that I claim the foregoing as my invention, I affix my signature, in the presence of two witnesses, this 25th day of August, 1922.

FRANK W. BARBER.
